US00D925506S

(12) **United States Design Patent** (10) **Patent No.:** **US D925,506 S**
Wang (45) **Date of Patent:** ** *Jul. 20, 2021

(54) **MICROPHONE**

(71) Applicant: **ZHAOQING JUNFENG ELECTRONICS CO LTD**, Guangdong (CN)

(72) Inventor: **Wanxuan Wang**, Guangdong (CN)

(73) Assignee: **ZHAOQING JUNFENG ELECTRONICS CO LTD**, Guangdong (CN)

(*) Notice: This patent is subject to a terminal disclaimer.

(**) Term: **15 Years**

(21) Appl. No.: **29/751,268**

(22) Filed: **Sep. 19, 2020**

(51) LOC (13) Cl. **14-01**

(52) U.S. Cl.

USPC **D14/228**

(57) **CLAIM**

The ornamental design for a microphone, as shown and described.

DESCRIPTION

FIG. 1 is a front perspective view of a microphone, showing my design.

FIG. 2 is a rear perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof; and,

FIG. 8 is a bottom plan view thereof.

The broken lines in the drawings depict environmental structure and boundaries and form no part of the claimed design.

1 Claim, 8 Drawing Sheets
